3 Claims. (Cl. 158—27.4)

Our invention relates to improvements in torches useful in the flame cutting of metals. In particular, the invention provides an improved flame cutting torch and a novel pressure regulation and gas flow control assembly for selectively controlling the pressure and flow of gases supplied to torches used in the machine of automatic cutting of metals.

Conventionally torches for flame cutting of metal are designed to utilize fuel gas, e.g. acetylene, propane or other combustible gas, and oxygen from tanks or cylinders at relatively high pressure for both combustion and for cutting. The higher the pressure, the greater is the efficiency although also the consumption of gases is higher. In ordinary torches, the oxygen and fuel gas are supplied at a constant tank pressure preset by a pressure type flow regulator associated with the supply tank. The pressure may be further adjusted by means of hand valves associated with the oxygen and fuel gas inlet pipes.

Usually, the pressure is of the order of 100 to 125 p.s.i.g. for the oxygen supply and 20 to 50 p.s.i.g. for the fuel supply, designed to provide, or approximate, a neutral flame for maximum heat during the preheating cycle. Additional oxygen for the cutting cycle is also made available at the regulated oxygen supply pressure through a separate line. Conventionally, the pressures are pre-set, and the mixture is adjusted by manual set valves. Usually lever means for switching from the preheat cycle to the cutting cycle is provided.

Operation with the combustion gases near or at the tank supply pressure is desirable for rapid and effective preheating, but is unnecessary for cutting, once preheating has been accomplished. Obviously, such operation is highly wasteful of fuel and oxygen and in addition, at the high temperatures obtaining, results in excessive tip consumption. Although conventional torches are ordinarily equipped with hand valves to permit adjustment of pressure (as well as mixture ratio) in the gas lines, the necessary adjustment is troublesome, time consuming and may be difficult to attain with the accuracy necessary for effective flame control. As a consequence, operators rarely attempt regulation by adjustment of valve settings to obtain optimum operation, in terms of pressure or mixture, as they switch from the metal preheating to the flame cutting cycles.

In recognition of this problem, injection type torches have been designed in order to promote efficiency of fuel utilization, which regulate flow of fuel gas by the volume and rate of flow of oxygen. The difficulty with such injection type torches, however, is that during the preheating cycle, the pressure (or flow) of combustion oxygen and fuel gas are so low that protracted heating times are required as a preliminary to cutting. For example, a period of $\frac{1}{2}$ to $1\frac{1}{2}$ minutes is customary in comparison to 4 to 10 seconds using flow at normal regulated tank pressures. The protracted preheating time over the usual work period results in excessive consumption of fuel gas, despite reduced combustion oxygen pressure. Also in significant additional cost, because of increased tip consumption, slower production rates, design complexity, and the like.

It is an object of the invention to provide an improved flame cutting torch, equipped with means for selectively regulating the pressure, flow and operation of both fuel gas and oxygen during the preheating and cutting cycles

2

in order to reduce consumption of fuel gas and oxygen which is susceptible of quick automatic control. It is a further object to provide a torch and burner, including an improved flow regulator valve assembly, which permits utilization of relatively inexpensive and readily available fuels such as propane and methane or other gases of petroleum origin. Another object is to reduce preheating time by improvement in control of the pressure and flow of combustion gases in a manner permitting speedup of production rates and, concomitantly, tip savings resulting from cool operating tips.

It is a further object of the invention to provide a pressure control assembly which is specially adapted for embodiment in machine torches used in assembly line or automatic operation.

According to the invention, a pressure control assembly is provided for controlling the flow of gas through the delivery tubes for combustion and cutting gases in flame cutting torches. The assembly essentially comprises a first control head for the combustion oxygen and fuel gas, a second control head for cutting oxygen, and lever means positioned between the two control heads in a manner permitting rapid switching from high to low pressure flow of the combustion gases while simultaneously opening the flow of cutting oxygen.

The first control head comprises a fuel gas inlet channel with a conduit from the channel to the fuel gas delivery tube and adjustable valve means associated therewith for controlling the flow of fuel gas. A bypass conduit is provided from the inlet channel to a valve chamber containing a quick acting valve such as a spring-loaded, plunger type valve. A conduit from the valve chamber to the fuel gas delivery tube contains an elongated valve stem which is adapted to actuate the valve when pressure is applied to the tip of the stem. Also, in the first flow control head a conduit is provided from an oxygen inlet channel to the combustion oxygen delivery tube. Adjustable valve means is provided for controlling the flow of oxygen through the conduit. A second conduit from the oxygen inlet channel is provided to the combustion oxygen delivery tube. Quick-acting valve means comprising a spring-loaded valve member and a reciprocable stem adapted to open and close the valve member is provided for controlling the flow of combustion oxygen through the second conduit in a manner similar to that of fuel gas.

The second control head comprises a conduit from the oxygen inlet channel to the cutting oxygen delivery tube. Quick-acting valve means comprising a spring-loaded valve member and reciprocable valve stem adapted to open and close such member provides control of cutting oxygen.

The lever means is located between the two flow control heads and essentially comprises a rotatably mounted cam adapted by means of a lobe to apply pressure alternately against the valve stem of the second control stem thereby switching from high to low pressure flow of the combustion gases while opening flow of cutting gas.

The invention will be further described by reference to the accompanying drawings, illustrating in particular embodiment of the invention, wherein:

FIGURE 1 is an elevational view showing a torch utilizing the invention in profile and in partial longitudinal section.

FIGURE 2 is a plan view partially sectionalized and cut away of the torch of FIGURE 1.

FIGURE 3 is an end view of the torch.

FIGURE 4 is partial section through the portion of the torch shown in FIGURE 3.

FIGURE 5 is a detail of the control head of FIGURE 2 in longitudinal section.

FIGURE 6 is a perspective section, partially broken away, of the torch.

In FIGURE 1, the essential parts of the torch may be seen: the combustion gas pressure control head 10, the cutting oxygen control head 11, the lever control system 12 situated between the two pressure control heads, the mixing head assembly 13, the burner tip 14, and the individual gas delivery tubes, respectively, the cutting oxygen tube 15, the combustion oxygen tube 16 and the fuel gas tube 17.

Control head 10 is best seen in FIGURE 5. Fuel gas is charged to the torch in the usual manner by means of threaded connection 20. Fuel gas inlet channel 21 is machined or bored in the head and provides a passageway for flow of fuel gas to tube 17 via conduit 22. An adjustable valve, for example, a conventional threaded needle valve 23 controls flow from inlet channel 21 and conduit 22 to delivery tube 17. A second conduit 24 connects the inlet channel 21 with a valve chamber 25 which contains a spring-loaded plunger valve 26. A cylindrical conduit 27 provides a passageway from valve chamber 25, via a connecting conduit 27a, to the combustion gas tube 17. An elongated valve stem 28, is reciprocably mounted in conduit 27. The tip of valve stem or rod 28 projects as indicated at 29 beyond the packing gland 30 and nut 31.

Oxygen is charged to the pressure control assembly through thread connection 32 which opens into inlet channel 33. Conduit 34 provides a connection from inlet channel 33 to combustion oxygen delivery tube 16. Threaded needle valve 35 is provided for manual adjustment of flow through the system. From the inlet channel 33, conduits 36 and 37 control such flow. A spring-loaded valve member 40 is contained in valve chamber 38, which in turn communicates by means for an elongated cylindrical conduit 41 and associated connection passage 41a with combustion oxygen delivery tube 16. Reciprocable in conduit 41 is elongated valve stem 42 of valve member 40. The tip 43 of the rod type plunger valve stem 42 projects beyond the packing gland 44 and nut 45.

Flow of oxygen from the inlet channel to the cutting oxygen system is provided by a conduit 45a which connects with section 15a of cutting oxygen delivery tube 15 and terminates in the second flow control head 11. Communication from section 15a is via conduits, 46 and 47, the latter of which opens into valve chamber 48. Spring-loaded valve member 49 is operative in chamber 48 and is actuated by rod member 50 which is reciprocable in conduit 47. Tip 51 of the rod type valve stem 50 projects beyond the packing gland 52 and associated nut 53. Conduit 54 provides a connection between valve chamber 48 and cutting oxygen delivery tube 15.

The openings from oxygen inlet channel 33 to conduits 34, 36 and 45a may be seen in FIG. 4 where they are designated respectively as 33a, 33b and 33c.

The lever control system, operative between the two flow control heads 10 and 11, comprises rotatably mounted cam 60 which is designed preferably to have two lobes 61 and 62. As shown, the lobes are set approximately 90° apart. Cam 60 is rotated by action of lever arm 63 in a manner which may alternately apply actuating pressure, upon valve stem tips 29 and 43, which advantageously are paired by means of bar 64, and on valve stem tip 51. Because of the resulting reversed reciprocation of the valve stems, valves 26 and 40 are opened while valve 49 closes, and vice versa.

It will thus be apparent that in operation, the torch can be "lighted up" with lever arm 63 and cam 60 in the neutral, or central position. In such position, the three spring-loaded plunger valves 26, 40, and 49 are closed. Hence, flow of combustion oxygen and fuel gas flow through the passageways and restrictive orifices (to obtain design pressure drops) under control of needle valves 23 and 35 as normally preset. For preheat, lever arm 63 is moved in the direction indicated by arrow 65, thereby

forcing lobe 61 of cam 60 against yoke bar 64 and valve stem tips 29 and 43. As a consequence, valves 26 and 40 are opened and additional combustion oxygen and fuel gas flow individually through valve chambers 38 and 25 respectively, to provide high pressure preheating combustion conditions at the tip. The result is rapid preheating, with significant gas savings. Upon the completion of preheating, the position of lever arm 63 is reversed to that shown in FIGURE 6, which has the effect of forcing cam lobe 62 against valve stem tip 51, while at the same time releasing valve stem tips 29 and 43. The effect is to return the flow of combustion gases to a low pressure condition while simultaneously opening the flow of cutting oxygen at high pressure. The leverage control system, located between the two pressure control heads, provides a remarkably simple system for selective control of the pressure and flow of combustion cutting gases in flame cutting torches. Gas and tip economies are effected, and greater flexibility in utilization of lower B.t.u. gases is provided. Because of the simplicity of mechanical design the assembly can be designed as a unit adapted for use with a variety of different torches. The simplicity and ease in design and operation of the lever control system also makes the assembly particularly suited for use with machine operated torches, particularly those of the vertical type, which are used in multiple sets in the automated flame cutting of metal.

We claim:

1. A pressure control assembly for controlling flow of gases through delivery tubes for combustion and cutting gases in a flame cutting torch which comprises a first control head containing a fuel gas inlet channel, a conduit from said channel to a fuel gas delivery tube, adjustable valve means associated therewith for controlling flow of the gas therethrough, a conduit from said fuel gas inlet channel to the fuel gas delivery tube, quick-acting valve means comprising a spring-loaded valve member and a reciprocable stem adapted to open and close said valve means associated with said conduit for controlling flow of fuel gas therethrough, an oxygen inlet channel, a conduit from said oxygen inlet channel to a combustion oxygen delivery tube, adjustable valve means associated therewith for controlling flow of the oxygen gas therethrough, a second conduit from said oxygen inlet channel to the combustion oxygen delivery tube, quick-acting valve means comprising a spring-loaded valve member and a reciprocable stem adapted to open and close said valve means associated with said conduit for controlling flow of combustion oxygen therethrough, a second control head for cutting oxygen comprising a conduit from the oxygen inlet channel to a cutting oxygen delivery tube, a quick-acting valve means comprising a spring-loaded valve member and a reciprocable stem adapted to open and close said valve means associated with said conduit for controlling flow of cutting oxygen therethrough and lever means positioned between said first and second flow control heads comprising a rotatably mounted cam adapted via a lobe thereof to apply pressure alternately against the valve stems of said first control head and against the valve stem of said second control head thereby switching from high to low pressure flow of combustion gases while opening flow of cutting gas, and a lever rod adapted to actuate said cam.
2. In a flame cutting torch comprising a mixing head, burner tip, and separate tubes for delivering fuel gas, combustion oxygen and cutting oxygen to said mixing head and burner tip, a pressure control assembly for controlling flow of gas and oxygen through said delivery tubes which includes a first control head for combustion gases including a fuel gas inlet channel, a conduit from said channel to said fuel gas delivery tube, adjustable valve means associated therewith for controlling flow of the gas therethrough, a valve chamber, a conduit from said fuel gas inlet channel to said valve chamber a spring-loaded plunger-type valve in said valve chamber, an elongated cy-

cylindrical conduit and a connecting conduit means from said valve chamber to the fuel gas delivery tube, an elongated valve stem reciprocable in said cylindrical conduit, an oxygen inlet channel, a conduit from said oxygen inlet channel to the combustion oxygen delivery tube, adjustable valve means associated therewith for controlling flow of the oxygen gas therethrough, a valve chamber, a spring-loaded plunger-type valve in said chamber, a second conduit from said oxygen inlet to said valve chamber, an elongated cylindrical conduit and an associated connection passage communicating said valve chamber with said combustion oxygen delivery tube, an elongated valve stem reciprocable in said elongated conduit, a second control head for cutting oxygen comprising a valve chamber, a spring-loaded plunger-type valve in said chamber, a conduit from the oxygen inlet channel to said valve chamber, an elongated cylindrical conduit and passage means communicating said valve chamber with the cutting oxygen tube, an elongated valve stem reciprocable in said cylindrical conduit and lever means positioned between said first and second flow control heads comprising a rotatably mounted cam adapted via a lobe thereof to apply pressure alternately against the valve stems of said first control head and against the valve stem of said second control head thereby switching from high to low pressure flow of combustion gases while opening flow of cutting gas, and a lever rod adapted to actuate said cam.

3. In a flame cutting torch comprising a mixing head, burner tip, and separate tubes for delivering fuel gas, combustion oxygen and cutting oxygen to said mixing head and burner tip, a pressure control assembly for controlling flow of gas and oxygen through said delivery tubes which includes a first control head for combustion gases comprising a fuel gas inlet channel, a conduit from said channel to said fuel gas delivery tube, adjustable valve means associated therewith for controlling flow of the gas therethrough, a conduit from said fuel gas inlet channel

10 to the fuel gas delivery tube, quick-acting valve means comprising a spring-loaded valve member and a reciprocable stem adapted to open and close said valve means associated with said conduit for controlling flow of fuel gas therethrough, an oxygen inlet channel, a conduit from said oxygen inlet channel to the combustion oxygen delivery tube, adjustable valve means associated therewith for controlling flow of the oxygen gas therethrough, a second conduit from said oxygen inlet channel to the combustion oxygen delivery tube, quick-acting valve means comprising a spring-loaded valve member and a reciprocable stem adapted to open and close said valve means associated with said conduit for controlling flow of combustion gas therethrough, a second control head for cutting oxygen comprising a conduit from the oxygen inlet channel to the cutting oxygen delivery tube, quick-acting valve means comprising a spring-loaded valve member and a reciprocable stem adapted to open and close said valve means associated with said conduit for controlling flow of cutting oxygen therethrough, and lever means positioned between said first and second flow control heads comprising a rotatably mounted cam adapted via a lobe thereof to apply pressure alternately against the valve stems of said first control head and against the valve stem of said second control head thereby switching from high to low pressure flow of combustion gases while opening flow of cutting gas, and a lever rod adapted to actuate said cam.
